(57) **CLAIM**

The ornamental design for a foldable solar charger, as shown and described.

DESCRIPTION

FIG. 1 is a front elevational view of a foldable solar charger showing our new design in a folded state;

FIG. 2 is a rear elevational view of FIG. 1;

FIG. 3 is a left side view of FIG. 1;

FIG. 4 is a right side view of FIG. 1;

FIG. 5 is a top plan view of FIG. 1;

FIG. 6 is a bottom plan view of FIG. 1;

FIG. 7 is a top, front and left side perspective view of FIG. 1;

FIG. 8 is a bottom, rear and left side perspective view of FIG. 1;

FIG. 9 is a front elevational view showing the foldable solar charger in an open state;

FIG. 10 is a rear elevational view of FIG. 9;

FIG. 11 is a left side view of FIG. 9;

FIG. 12 is a right side view of FIG. 9;

FIG. 13 is a top plan view of FIG. 9;

FIG. 14 is a bottom plan view of FIG. 9;

FIG. 15 is a bottom, front and right side perspective view of FIG. 9;

FIG. 16 is a top, rear and left side perspective view of FIG. 9; and,

FIG. 17 is a top, rear and right side perspective view showing the foldable solar charger in a use state.

The broken lines in the drawings illustrate portions of the foldable solar charger which form no part of the claimed design.

1 Claim, 17 Drawing Sheets
